UNITED STATES PATENT OFFICE.

ELBRIDGE C. COLLINS, OF DETROIT, MICHIGAN.

POWER-GENERATING APPARATUS.

1,272,378.

Specification of Letters Patent. Patented July 16, 1918.

Application filed January 26, 1916, Serial No. 74,410. Renewed January 8, 1918. Serial No. 210,948.

To all whom it may concern:

Be it known that I, ELBRIDGE C. COLLINS, a citizen of the United States, and a resident of Detroit, in the county of Wayne 5 and State of Michigan, have invented a certain new and useful Improvement in Power-Generating Apparatus, of which the following is a specification.

My present invention relates generally to 10 power plants, and more particularly to apparatus for generating power through the use of an impact engine, and the production, control, and continuous use of an expansible liquefiable gas as an impact fluid 15 therefor, my object being to provide an effective apparatus of this character which will be simple and inexpensive as well as durable, which will permit of ready and easy control, and which may be erected 20 within minimum space.

My invention further and particularly consists in the apparatus to be now described with reference to the accompanying drawing, forming a part of this specification, 25 and in which the figure is a diagrammatic view of the entire plant, certain of the parts being shown in section, as herein-after referred to.

As shown in the drawing, my invention 30 contemplates the provision of a reservoir A having a valved inlet pipe A' leading into its upper end for supplying a suitable volatile or liquefiable gas, such as sulfur dioxid or anhydrous ammonia, the gas so 35 supplied being in liquid form.

From the base of the reservoir A leads 40 a pipe B, controlled by a valve B', pipe B depending into the upper end of a supply tank C, from the lower end of which a pipe D depends and is controlled by a valve D'.

The pipe D extends downwardly into a 45 generator E having a vent E' at its upper end and adapted to contain a heated fluid such as water, with or without calcium chlorid or oil, the heating of the fluid within the generator E being effected in any suitable manner, as by means of a steam or electric coil F having inlet and outlet pipes F' and F² respectively communicating between the same and the lower and upper ends of the generator.

The lower end of the pipe D within the generator E is connected to one end of a high pressure coil G, to the opposite end of 55 which is connected one end of a gas pipe H, it being noted that the high pressure

coil G is entirely surrounded by the heated liquid within the generator before mentioned.

The opposite end of the pipe H leads to 60 the impact engine preferably in the form of a turbine, as seen at I, and is controlled by a valve H', the exhaust pipe J leading from said turbine and controlled by a valve J', being extended upwardly and connected 65 to one end of the coil K' of a condenser K, the opposite end of which coil K' is connected to a pipe M, through a valve M', which latter pipe leads into the upper end 70 of the reservoir A.

The shaft I' of the turbine I may be extended to any suitable point from which it is desired to take power therefrom, or may be utilized in any other suitable manner, as for instance, to drive a dynamo indicated 75 at I².

A pressure equalizing pipe N extends from the gas or high pressure pipe H as shown, and is provided with a controlling valve N' adjacent said pipe. Pressure 80 equalizing pipe N is also provided with branches N² and N³, each controlled by its respective valve N⁴ and leading respectively into the upper end of the reservoir A and the supply tank C. 85

Thus in operation with the high pressure coil G heated to a desired temperature by the liquid within the generator E maintained at, for instance, 104° F., and with a supply of liquid gas in the reservoir A, the 90 valve B' is opened permitting a quantity of the liquid to pass into the supply tank C by gravity, the valve B' being then closed and valve D' opened to permit the liquid 95 from the supply tank C to pass downwardly to the high pressure coil G through pipe D. The liquid so finding its way into the high pressure coil, is promptly changed to its gaseous form, and in doing so expands to a high pressure and in such form 100 and at such pressure passes through the gas or high pressure pipe H to the turbine I, valve H' having been opened. The valve N' of the pressure equalizing pipe N is then opened and valve N⁴ of its branch 105 N³ also opened to permit of the passage of pressure within the supply tank C in order to balance the pressure above and below the supply of liquid gas therein, and permit of continuous feed of the liquid downwardly 110 by gravity.

The gas at high pressure having been

utilized in the turbine I to drive its shaft I', passes through the exhaust pipe J, valve J' of which has been opened, to the condenser K, passing through the coil thereof 5 and after condensation and in liquid form, finding its way again to the reservoir A through the pipe M, valve M' of which has been opened.

The main valve B' may then at any time 10 be opened, and by opening valve N⁴ of branch N² of the equalizing pipe N, pressure may be introduced into the upper end of the reservoir A to feed a supply of liquid downwardly into the supply tank C.

15 If, for any reason, in the use of the apparatus the turbine I is temporarily shut down, or if the pressure of its gas generated as above described at any time and for any reason exceeds the demands of the turbine, 20 the generated gas or the excess thereof, may pass directly from the high pressure or gas pipe H to the exhaust pipe J at a point above the valve J' of the latter and thus directly in communication with the condenser, through a by-pass O in which a relief valve O' is mounted.

The reservoir A and supply tank C may be respectively provided with pressure indicators A² and C², and a pipe P may 30 lead from the base of the supply tank C, through a cut-off valve P' and a regulating valve P² to a pump Q, the discharge pipe R of which, having a valve R', leads to the pipe D before mentioned at a point below 35 the valve D' thereof.

Thus the pressure equalizing branches N² and N³ may be cut off by closing valves N⁴ in each of these pipes, and the supply of liquid gas to the high pressure coil G 40 effected through the pump Q. In this event, the regulating valve P² is controlled by its pressure pipe P³ leading from the pressure equalizing pipe N and having a controlling valve P⁴.

45 Thus from the foregoing it will be seen that I provide an apparatus of a simple and inexpensive nature, capable of ready and convenient control and erection within a minimum space, and which will be durable 50 and effective in its operation.

I claim:—

1. In an apparatus of the character described, a reservoir having a valved inlet and a valved outlet depending therefrom, a 55 supply tank into which said outlet depends, having a depending valved pipe, a fluid holding generator, means for heating the fluid within said generator, a high pressure coil within said generator and to one end 60 of which said supply tank pipe is connected, a valved high pressure gas pipe leading from the opposite end of said coil, an impact member to which said gas pipe leads, a condenser, an exhaust pipe leading from the 65 said impact member to the said condenser,

a valved pipe leading from the condenser into said reservoir, a pressure equalizing pipe leading from said high pressure gas pipe, a feed pump for feeding liquid gas into the high pressure coil, having an intake 70 pipe communicating with said supply tank, and a regulating valve in said intake pipe having a controlling pressure pipe leading into said pressure equalizing pipe.

2. In an apparatus of the character de- 75 scribed, a reservoir having a valved inlet and a valved outlet depending therefrom, a supply tank into which said outlet depends, having a depending valved pipe, a fluid holding generator, means for heating the 80 fluid within said generator, a high pressure coil within said generator and to one end of which said supply tank pipe is connected, a valved high pressure gas pipe leading from the opposite end of said coil, an im- 85 pact member to which said gas pipe leads, a condenser, an exhaust pipe leading from the said impact member to the said condenser, a valved pipe leading from the condenser into said reservoir, a pressure equal- 90 izing pipe leading from said high pressure gas pipe, and having valved branches re- spectively communicating with said reservoir and said supply tank.

3. In an apparatus of the character de- 95 scribed, a reservoir having a valved inlet and a valved outlet depending therefrom, a supply tank into which said outlet depends having a depending valved pipe, a fluid holding generator, a high pressure coil with- 100 in said generator and to one end of which said supply tank is connected, a valved high pressure gas pipe leading from the opposite end of said coil, an impact member to which said gas pipe leads, a condenser, an exhaust leading from the said impact mem- 105 ber to the condenser, and a valved pipe lead- 110 ing from the condenser into the said res- ervoir.

4. In an apparatus of the character de- 110 scribed, a generator including a high pres- sure coil, a supply tank communicating with said generator coil, a high pressure gas pipe also communicating with said coil, an im- 115 pact member to which said gas pipe leads, a condenser connected to the exhaust side of said impact member, a reservoir with which said condenser communicates, having a valved connection with said supply tank, and a valved pressure equalizing pipe lead- 120 ing from said high pressure gas pipe and having valved branches respectively com- 125 municating with said reservoir and with said supply tank.

5. In an apparatus of the character de- 125 scribed, a generator including a high pres- sure coil, a supply tank communicating with said generator coil, a high pressure gas pipe also communicating with said coil, an im- 130 pact member to which said gas pipe leads,

- a condenser connected to the exhaust side of said impact member, a reservoir with which said condenser communicates, having a valved connection with said supply tank, and valved pressure equalizing connections between said gas pipe and said reservoir and supply tank. 5
6. In an apparatus of the character described, a reservoir having a valved inlet and a valved outlet depending therefrom, a supply tank into which said outlet depends having a depending valved pipe, a fluid holding generator, a high pressure coil within said generator and to one end of which 10 said supply tank is connected, a valved high pressure gas pipe leading from the opposite end of said coil, an impact member to which said gas pipe leads, a condenser, an exhaust leading from the said impact member to 15 the condenser, a valved pipe leading from the condenser into the said reservoir, and a pipe extending directly between said gas pipe and said exhaust pipe and having a relief valve therein for the purpose described. 20
7. In an apparatus of the character described, a generator including a high pressure coil, a supply tank, a high pressure gas pipe communicating with said coil, an impact member to which said gas pipe leads, 30 a condenser connected to the exhaust side of said impact member, a reservoir with which said condenser communicates, having a valved connection with said supply tank, a feed pump for feeding liquid gas into the 35 high pressure coil having an intake pipe communicating with said supply tank, and a regulating valve in said intake pipe having a controlling pressure pipe communicating with said high pressure gas pipe. 40
8. A power apparatus including a supply tank for the reception of gas in liquid form, a generator having a closed coil in which the liquid is transformed into a gas at high pressure, an impact member to the working 45 chamber of which the gas is fed directly from the generator coil, having an exhaust pipe, a condenser communicating with the said exhaust pipe of the impact member and having valved connection with the said supply tank, and means for feeding the liquid from the supply tank directly into the said 50 generator.

ELBRIDGE C. COLLINS.
